GEORGE M. LITTLE, OF PITTSBURGH, PENNSYLVANIA, ASSIGNOR TO WESTINGHOUSE ELECTRIC AND MANUFACTURING COMPANY, A CORPORATION OF PENNSYLVANIA.

ARC-LAMP.

1,333,665.

Specification of Letters Patent. Patented Mar. 16, 1920.

Application filed November 12, 1915. Serial No. 61,049.

To all whom it may concern:

Be it known that I, GEORGE M. LITTLE, a citizen of the United States, and a resident of Pittsburgh, in the county of Allegheny and State of Pennsylvania, have invented a new and useful Improvement in Arc-Lamps, of which the following is a specification.

My invention relates to arc lamps and particularly to such lamps as are provided with electrodes containing ingredients which, when projected into the arc, render the arc flaming or highly luminous and engender fumes which tend to attack and etch the globe surrounding the electrodes.

15 The object of my invention is to provide an arc lamp of the above-indicated character with means for preventing the fumes within the lamp from attacking the glass or metal parts associated with the electrodes. 20 I accomplish this result by introducing into the arcing chamber a small amount of a vapor or a volatile substance which, when volatilized, is capable of neutralizing the fumes, the neutralizing agent being preferably of such character that it also covers the surfaces exposed to the fumes with a transparent protecting coating.

It has heretofore been customary to provide flaming arc lamps with a condensing chamber disposed above and in communication with the arcing chamber and containing pieces of magnesia or other solid basic material which are intended to absorb and neutralize any acid fumes that may be brought into contact with it during the operation of the lamp. I have discovered that the acid fumes may be much more effectively neutralized by introducing a small amount of a vapor or a somewhat volatile substance 35 having basic characteristics into the arcing chamber, such substance being either a gas, a volatile liquid or a solid capable of generating gas when heated. The gaseous or vaporous basic material which fills the globe 40 and the condenser during the operation of the lamp reacts with the acid fumes substantially as fast as they are produced in the arc.

A large number of substances are suitable for use according to my present invention, but I prefer to employ organic amines, which are bodies of the ammonia type and which react as bases with respect to acids such as those present in arcing fumes. Of 55 these substances, I find that anilin is a con-

venient and effective material, and a few cubic centimeters of this substance, when poured upon an absorbent pad of asbestos or the like, and deposited in the arcing chamber of a flaming arc lamp, are sufficient 60 to materially protect both metal and glass from the etching effect of the fumes. It is desirable, however, to continue also the use of the ordinary magnesia consumer.

Vapors of anilin and other amines, in addition to neutralizing the acid fumes produced by the arc during the first few hours of burning, operate to protect the exposed surfaces of the lamp in still another manner, by covering such surfaces with an exceedingly thin coating which is solidified by the heat of the arc into a solid varnish-like and transparent layer. This coating protects the exposed surfaces by mechanically preventing the fumes from reaching them. 75

Ordinary ammonia gas operates like the organic amines mentioned above in neutralizing the arc fumes, but, as ammonia forms no permanent protecting film upon the exposed surfaces, I prefer to make use of 80 anilin or some other of the amines.

One embodiment of my invention is illustrated in the accompanying drawing, the single figure of which is a side view, mainly in elevation but partly in section, showing 85 a flaming arc lamp having my invention applied thereto.

The lamp comprises the usual coöperating electrodes 1 and 2, an inner globe 3, an outer globe 4, a condensing chamber 5 and a casing 6 for inclosing the operating mechanism of the lamp. Disposed within the inner globe 3 is a pad 7 of asbestos or other absorbent material which has been impregnated with anilin or other substance capable 90 of evolving basic vapors and dropped into the globe while trimming the lamp. The absorbent pad is desirable but not absolutely necessary, as the liquid may merely be poured into the globe. 100

The volatile neutralizing agents mentioned above are preferably used in connection with the magnesia "consumer" ordinarily used in lamps of this character, but the volatile protecting agents may be used 105 alone.

One advantage possessed by my volatile neutralizing agents, in comparison with the ordinary magnesia "consumer", is that the acid fumes developed when the lamp is 110

first started are immediately neutralized. The most vigorous etching effect within an arc lamp takes place at the beginning of its operation when both acid fumes and moisture are present. An inclosed flame lamp, no matter how well it is cleaned, always has some sooty deposit adhering to inaccessible places. This deposit and the blocks of magnesia ordinarily used as fume consumers absorb a considerable amount of moisture from the air when the lamp is opened to be cleaned, and the newly trimmed electrodes may themselves contain some moisture. It therefore usually happens that, when the lamp is first lighted, it contains a substantially moist atmosphere which assists the acid fumes in attacking the exposed surfaces of glass and metal. This effect can obviously be only partially prevented by the ordinary blocks of magnesia disposed, as is usual, in a relatively inaccessible corner of the condensing chamber.

My present invention is not limited to any special construction of arc lamp or to the use of any specific protective substances except as such limitations appear in the appended claims.

I claim as my invention:

1. In an arc lamp, a pair of coöperating electrodes and a globe surrounding the said electrodes and containing a fluid the vapor of which is capable of forming a protecting coating upon the surfaces that are exposed to the said fumes.
2. In an arc lamp, a pair of coöperating electrodes and a globe surrounding the said electrodes and containing a fluid the vapor of which is capable of neutralizing the fumes produced by the arc and also capable of forming a protecting coating upon the surfaces that are exposed to the said fumes.

3. In an arc lamp, a pair of coöperating electrodes and a globe surrounding the said electrodes and containing an organic amine capable when heated of forming an arc-fume resistant coating upon the globe. 45

4. In an arc lamp, a pair of coöperating electrodes and a globe surrounding the said electrodes and containing anilin.

5. In an arc lamp, an arcing chamber, 50 electrodes therein, and absorbent means therein containing a liquid amine capable, when heated, of forming an arc-fume resistant coating upon such surfaces as are exposed to the said fumes. 55

6. In an arc lamp, an arcing chamber, electrodes therein, and means operating through the heat of the lamp to cover the surfaces exposed to arc fumes with a protective coating derived from an amine. 60

7. In a lamp, the combination with a globe and a light-giving member that detrimentally affects the globe, of means responsive to the burning operation of said light-giving member for forming a protective 65 coating on the globe.

8. In a lamp, the combination with a globe and a light-giving member that detrimentally affects the globe, of means responsive to the burning operation of said light-giving member for forming a relatively durable protective coating on the globe. 70

9. In a lamp, the combination with a globe and a light-giving member that detrimentally affects the globe, of means responsive to the burning operation of said light-giving member for forming a transparent protective coating on the globe. 75

In testimony whereof I have hereunto subscribed my name this 29th day of Oct., 1915. 80

GEORGE M. LITTLE.
